UNITED STATES PATENT OFFICE

ARTHUR E. PEW, JR., OF BRYN MAWR, PENNSYLVANIA, ASSIGNOR TO SUN OIL COMPANY, OF PHILADELPHIA, PENNSYLVANIA, A CORPORATION OF NEW JERSEY

APPARATUS FOR DISTILLING LUBRICATING OIL

Application filed May 29, 1926, Serial No. 112,485. Renewed August 21, 1929.

My invention relates to the treatment, condensation and deodorization of vapor from an oil still, and particularly from a continuous oil still operating in accordance with any process adapted to evolve vapors that may or may not be free from products of decomposition but containing heavier fractions which it is desired to eliminate and products which if retained would impart an offensive or disagreeable odor to the distillate. The object of my invention is to condense and separate such heavier fractions and return them to the still and to separately condense the remaining vapors and to eliminate therefrom all incondensable gases and other odor-producing products.

A preferred embodiment of my invention is shown in the accompanying drawings, in which—

Fig. 1 is a diagram, in side elevation, of the principal elements of a complete distillation plant. Fig. 2 is an end elevation of the same.

Fig. 3 is a detail elevation view, mainly in section, of the refluxing and condensing tower.

Fig. 4 is a plan view, and Fig. 5 an edge view, of one of the tile-supporting grids in the tower.

Fig. 6 is a detail sectional elevation of the deodorizer.

Fig. 7 is a partial view, also in section, of the deodorizer, looking at right angles to Fig. 6.

The invention is particularly adapted to the distillation of petroleum from which the lighter fractions have been topped so as to leave the fractions adapted for the manufacture of lubricating oil. The invention is applicable, however, to the distillation of any or all fractions of petroleum or any other similar crude or partly refined product of petroleum or other oil.

The oil to be distilled flows through a pipe *b* into the first vaporizer *a* of the series wherein the lightest fraction of the oil is vaporized. See Figs. 1 and 2. The residue, which constitutes the greatly predominating part of the admitted oil, flows out through pipe *b'* and thence into the next vaporizer *a'* of the series,

wherein another, and somewhat heavier fraction is evaporated. The same operation occurs in the other vaporizers *a*² and *a*³ of the series. *b*² and *b*³ are pipes for residue from *a'* and *a*², respectively. The final residue flows through pipe *b*⁴ to the tar tank *c*, which is connected with vacuum through pipe *c'*. There may be as many vaporizers as desired in the series. Any suitable heating medium may be employed, but I more particularly contemplate the use of mercury vapor as the direct heating medium and the use of a process and apparatus similar to that shown in an application filed by Arthur E. Pew, Jr. and Henry Thomas March 5, 1925, Serial No. 13,040. The use of the process therein disclosed permits of a relatively low temperature of the heating medium and is characterized by high heat conductivity, so that the vapors may be distilled without the necessity of subsequently purifying the distillate by chemical treatment or with fullers' earth.

The vapor condensing, refluxing and deodorizing apparatus herein set forth comprises a number of units, one for each vaporizer, and a description of one of the units will suffice to describe all.

The vapor from any vaporizer (say *a*) escapes through pipes *d* to a header *d'* and thence through pipes *d*² to the lower part of a tower *x* (see Figs. 3, 4 and 5). Just above the discharge mouths of pipes *d*², and not far above the bottom of the tower, is a grid *e*, which supports a pile of chemical tiles, preferably the well known Raschig rings, *f*. Above and spaced from the top of the pile of tiles *f* is another grid *g*, similar to grid *e*, and shown in detail in Figs. 4 and 5. Grid *g* supports another and higher pile of tiles *h*, which may be of the same character as tiles *f*.

Below grid *g* and above tiles *f*, and spaced from both, is a pan or partition *i* provided with an upstanding flange *i'* enclosing a central vapor passage. Secured to the bottom of grid *g* is a deflector *j*, which consists of an imperforate disc having a peripheral downwardly and obliquely extending flange whose periphery overhangs the annular space outside of the flange *i'* of partition *i*.

The bottom of the tower communicates, through a pipe *k*, with one of the vaporizers, preferably the same vaporizer as that from which the vapors passed into the bottom of the tower, and with that end of such vaporizer into which the main stream of oil is fed.

The top of the tower communicates, through a pipe *m'*, with a stink oil receiver *m*.

10 Any vapors carried into the tower *x* from pipes *d* that are heavier than the fraction which it is desired to segregate will condense while going through the tiles *f* and flow down to the bottom of the tower. Any particles 15 of oil that may possibly be entrained with the vapors will also flow to the bottom of the tower. Thence the condensate, or condensate and unvaporized oil, will return to the vaporizer through pipe *k* and join the ingo- 20

The uncondensed vapors will pass up through the central opening in pan *i*, through the annular space around deflector *j* and through grid *g*, and through the high pile of 25 tiles *h*, wherein the vapors are cooled and most of them condensed. The uncondensable gases, comprising mostly stink vapors, escape through stink pipe *m'* into the receiver *m*. The condensate flows back through the 30 tiles *h* and through the grid *g* into the annular oil receiving pan *i*. Thence the condensate passes through a pipe *n* (having a goose-neck providing a trap *n'*) into what I call a deodorizer *o*.

35 The distillate entering the deodorizer is in fairly good condition, but it carries with it some products that impart a somewhat undesirable odor to the oil and from which the oil should be freed.

40 The deodorizer, shown in small scale in Figs. 1 and 2 and in detail in Figs. 6 and 7, consists of an upright receiver, rectangular in cross section, provided with inclined staggered flow plates *p* down which the oil flows 45 and over which it is distributed in very shallow streams. Any vapors carried along with the oil and released therefrom during the flow of the oil through the deodorizer, as well as any part of the oil that may vaporize 50 during such flow, consist, wholly or largely, of odor-imparting products. They escape through pipes *r* into a header *r'*, which is connected, through a pipe *r*², with a vacuum line. The completely deodorized oil flows 55 out the bottom of the deodorizer through a pipe *s'*, which conveys the oil, through a cooler *s*², to a main receiver *s*.

The main receiver *s* and the stink oil receiver *m*, like the tar tank *c* and the header 60 *r'* of the deodorizer, should be provided with valved pipes connected with vacuum, in order that the oil flow system may be maintained under the degree of vacuum desired.

If the oil has been subjected to the mercury vapor process of distillation set forth

in the said Pew and Thomas application, the distilled fractions conveyed to the several receivers *s* are in such excellent condition that they require no purifying treatment to render them marketable.

Any efficient means adapted to distribute the oil and vapor over a wide surface to facilitate refluxing and condensation may be substituted for, and will be a mechanical equivalent of, the Raschig rings or chemical tiles hereinbefore mentioned.

I do not herein claim the herein described process of producing lubricating oil distillates which comprises subjecting liquid oil to thermal conditions adapted to produce condensable oil vapors containing odor-removing gas, removing the oil vapors and condensing them and distributing condensate over an extended area and while so distributing it subjecting it to a vacuum sufficiently high to remove odor-producing gases, nor do I claim herein any part or feature of said process or any other process herein described. The subject-matter herein claimed is restricted to the apparatus herein shown and described; the novel processes therein carried out being the subject-matter of pending applications, Serial No. 159,754, filed January 8, 1927, and Serial No. 181,911, filed August 27, 1926.

Having now fully described my invention, what I claim and desire to protect by Letters Patent is:

1. In an oil distilling apparatus, the combination with an oil vaporizing apparatus adapted to continuously receive oil and continuously form and discharge vapors, of a tower, a conduit adapted to convey oil vapors from the oil vaporizing apparatus to the lower part of the tower, means within the tower adapted to promote reflux fractional condensation of the vapors, the tower having a top outlet for uncondensed odor-producing gases, a conduit for the escape from the lower part of the tower of heavier condensate, and a conduit communicating with the tower substantially above the vapor inlet but substantially nearer the bottom of the tower than the top, for escape of lighter condensate, the height of the tower above the lighter condensate outlet being multiple times the diameter of the tower, and a deodorizer with which the second conduit communicates; the deodorizer comprising a receptacle, means therein adapted to distribute the lighter condensate in a thin film, gas outlets from the receptacle adapted for connection with vacuum, and a liquid discharge.

2. In an oil distilling and refining apparatus, the combination with an oil vaporizing apparatus, of a tower, a relatively shallow tier of tiles in the lower part of the tower, a relatively deep tier of tiles above the lower tier of tiles, a conduit for oil vapor communicating with the tower below the lower tier of tiles, an outlet for heavier condensate con-

ensed in the lower tier of tiles, an outlet for lighted condensate condensed in the upper tier of tiles, a deodorizer providing extended surfaces for the travel and distribution of oil
5 in a thin layer, an outlet for odor-producing gases in the upper part of the tower, a conduit leading from said outlet for lighter condensate to the deodorizer, connections to vacuum from the deodorizer for removing odor-
10 producing gases from the oil distributed and flowing through the deodorizer, and a conduit for conveying the deodorized oil from the deodorizer.

3. In an oil distilling apparatus, the combination with an oil vaporizing apparatus, of a tower, a lower grid within and relatively near the bottom of the tower, an upper grid within the tower above the lower grid and substantially more distant from the top of the
20 tower than from the lower grid, a tier of tiles on the lower grid and a relatively deeper tier of tiles on the upper grid, a partition having a vapor passage and an oil receptacle positioned below the upper grid, a deflector below
25 the upper grid and over the vapor passage in the partition, a conduit for vapor between the oil vaporizing apparatus and the space in the tower below the lower grid, an oil condensate return conduit from the lower part of the
30 tower below the lower grid to the vaporizing apparatus, an oil condensate outflow conduit from the oil receptacle of the partition, and a stink gas outlet at the top of the tower.

4. In an oil distilling apparatus, the combination with a series of oil vaporizers through which a stream of liquid oil is adapted to successively flow, a number of reflux condensate towers and a number of deodorizers having extended surfaces for the travel and distribution
35 of oil in a thin layer and in which odor-producing gases are adapted to be separated from the condensate, a tower and a deodorizer being connected in series with each other, a vapor outlet from each vaporizer to a corresponding tower, each tower and connected deodorizer being in multiple relation with respect to the other connected towers and deodorizers.

In testimony of which invention I have
50 hereunto set my hand at Marcus Hook, Pennsylvania, on this 14th day of May, 1926.

ARTHUR E. PEW, JR.
